P. E. EDELMAN

RADIO POWER SUPPLY UNIT

Filed March 23, 1925

FIG. 2.

INVENTOR.

Philip E. Edelman

Patented Aug. 14, 1928.

UNITED STATES PATENT OFFICE.

PHILIP E. EDELMAN, OF CHICAGO, ILLINOIS.

RADIO POWER-SUPPLY UNIT.

Application filed March 23, 1925. Serial No. 17,489.

This invention comprises certain new and useful arrangement of coacting electrical elements whose generic object is to provide a small compact electrical convertor unit having a plurality of output circuits suited for furnishing power supply to the cathode heating and the anode to cathode circuits of radio vacuum tubes, provided with means for eliminating objectionable hum in said output circuits, provided further with a grounded enclosure for said electrical elements whereby induction therefrom with respect to the ground is prevented from reaching radio apparatus to which said unit is to be connected. More specific objects of this invention provide a common transformer as primary source for all output circuits whereby the variations in current draw from each of said circuits tend to cooperate in the regulation of the combined output of said transformer. Also choke coils are distributed on both sides of the output pilot conductors whereby remaining fluctuations of current in the output due to capacity leakage with respect to the ground potential are eliminated. Further the output potential intended for plate supply to vacuum tubes of a radio set is adjustable via series resistances which do not comprise a shunt load limiting the output when a rectifier of small milliamperage output is used in the power unit, and do not cause the loss and voltage drop that a shunt potentiometer type of load regulator would. A further specific improvement comprised in this invention is that the storage elements and the choke coils can now be made much smaller in size than formerly required due to the operation of the filter systems starting at source end with much higher potential than at output end, each successive stage operating at a lower potential than the preceding stage, and in the case of the filament supply output circuit, the first storage cells having a higher output terminal voltage than the next cells of the series, thereby overcoming the resistance effect of smaller size of choke coils employed, so that a compact unit of small dimensions is obtained. The grounded enclosure for the elements also assists in dissipation of heat arising during operation. Further, to avoid radio frequency currents travelling back thru the pilot conductors of output circuits to cause undesired regenerative feedback effects in a radio set to which

this unit supplies power, the end terminals of said power unit are shunted with by-pass condensers, and the terminals are provided for universal use whether the connected radio set requires B minus to A plus or B minus to A minus, binding post connection.

Reference is made to the accompanying drawing of which Figure 1 is a diagram of the radio power supply unit, and Figure 2 is a detail of one of the cell elements 40 of Figure 1, shown in front elevation.

Present invention has for its object to provide a unit attachable to an alternating current lighting socket, to provide plural sources of direct current for use in operating one to eight, or more, vacuum tubes, as a current supply for both the filaments and the plates thereof. A further object is to accomplish the said result with an inexpensive compact unit insulated from the main power supply, provided with means to care for heat arising therein, and adapted to furnish constant sources of direct current free from objectionable alternating current hum. The invention comprises certain new combinations whereby said result is attained and various changes may be made without departing from the general means set forth, within the scope of the appended claims.

Referring now, more particularly, to Figure 1—an ordinary attachment plug 1, connects by a flexible cord conductor 60, via a fuse 2, to the primary winding 4, of an alternating current transformer 3. This transformer 3, has a plurality of secondary output windings 5, 6, 7 and 8, and is constructed in usual closed core manner well known in the art. An impedance coil 10, is connected to the winding 5, and has a divided winding 11, 12 with a middle connection 13. The terminal 13, connects with a series of closed core choke coils 14, 15, 16, 17, wire 61, and the terminal post 32. This terminal 32, may be labeled "Minus B," indicating that this is the correct connection for the "minus B" binding post or terminal of a standard radio set.

One terminal 62, of transformer coil 5, is also connected to an anode 51, of rectifier 45. The cathode 48, of rectifier 45, is connected to transformer winding 7, via rheostat 43. The cathode 48, is connected to choke coil 24, thence to choke coil 27, into rheostats 25, 26, then to wires 63, 64 and terminal posts 31, 30. Terminal post

31 may be labeled "Plus B detector." Post 30, may be labeled "Plus B amplifiers," for the same purpose already set forth.

The resistances 25 and 26 being connected 5 in series with condenser 23 and terminals 30, 31, 32, have a novel effect in limiting the current discharge from condenser 23. The amount of current which resistances 25 or 26 can pass takes an appreciable time to flow 10 from condenser 23 through the high resistance thereof and in the meantime this condenser 23 receives a fresh charge. This effect is similar to a fly wheel on an engine provided with governor and smoothes out 15 the current to prevent sudden fluctuations as the load varies or the input voltage to plug 1 changes. Also these resistances 25 or 26 being in series connection do not act as a power controlling load on the circuit 20 except when current is passing through said resistances for useful purpose in actuating the connected radio set.

A plurality of by-pass condensers 19, 20, 21, 22, 23, are respectively connected 25 between the choke coils 14 and 24, 15 and 24, 16 and 24, 17 and 24, 18 and 24, to serve as a storage and filter system. These condensers may be of the well known paper or mica type. The sizes of the said choke coils and 30 the said condensers are proportioned as is well known in the art, in accordance with the alternating current frequency of the source used to supply the transformer 3, and to take care of harmonics thereof. The 35 combined inductance of the choke coils above enumerated may, for example, be fifty henries, while the combined capacity of the condensers enumerated above, may, for example, be six micro-farads.

40 Two terminal condensers, 28, 29, are connected between the posts 30, 31, and 32, as shown and are preferably placed at the ends of wires 64, 63 and 61, which are intended to reach near to the connected radio set (not 45 shown) in order that any radio frequency currents may not need to flow thru wires 64, 63 and 61.

A second rectifier 44, is similarly connected with its anode 52, supplied by transformer winding 5, and with its cathode 47, supplied by transformer winding 7, via rheostat 43. The function of the impedance coil 10, is to balance the currents fed to the two anodes 52, 51, whereby both half cycles 55 of the alternating current will be substantially equally rectified by the rectifiers 44, 45, even when the cathodes 47, 48, are dissimilar in dimensions, or when the vacuum in the rectifier tubes 44, 45, vary from each 60 other.

The above description covers a full wave rectifier supplying a special series filter with an adjustable potential output, having terminals provided with by-pass condensers 65 28, 29, and would still be operative if either

the rectifier 44, or 45 were omitted, in such case using only one rectifier for half wave rectification. Instead of vacuum tube type of rectifiers, electrolytic or mechanical types may be used; preferably, however, a bulb type of standard rectifier or vacuum tube is used.

The transformer winding 6, connects with the anode 50, of rectifier 46, whose cathode 49, is heated by transformer winding 8. One terminal 65, of transformer winding 6, is connected to a choke coil 39. One terminal 66, of transformer winding 8, is connected to a choke coil 38. A current storage unit 40, is connected to choke coils 38 and 39. This unit may comprise a small sized storage battery or may comprise one or more electrolytic condensers, or, electrolytic rectifiers such as the aluminum-lead or tantalum-lead types, well known in the art. The storage unit 40, may be of the lead-acid-lead type or of the nickel-alkaline-iron type in case it is comprised as a floating battery instead of an electrolytic condenser.

A second current storage unit 41, is connected to the unit 40, via a choke coil 37. If desired, and as shown, a third current storage unit 42, may be connected to the first and second above named storage units via a choke coil 35; this may be continued in similar cascaded connections as far as may be necessary to remove noticeable alternating current fluctuations. Usually it suffices to have two or at most three of such cascaded current storage units to obtain a 1 terminal direct current source which is practically free from alternating current ripples. If desired, a rheostat 59, may be included to vary a current obtainable at the terminals 33, and 34. Terminal 33, may be 10 labeled "Plus A" while terminal 34, may be labeled "Minus A."

A metal container 53, having vent holes 67, is provided to house the above named elements and is electrically connected by 11 wire 68 to wire 69, and grounded. A unit of this description which I have constructed and used has a box 53, of size 8" x 10" x 10".

The above continued description has covered the part of the unit comprising means 11 for supplying filament current to vacuum tubes. Owing to the current storage units described, the filaments of one to eight or more standard vacuum tubes, (not shown) can be heated in usual parallel connection. 12 The several choke coils above described are preferably constructed with laminated iron closed cores. In the case of the choke coils 37, and 35, it is desirable to have relatively large sized wire for the coils thereof and to 12 proportion the resistance of each winding so that the direct current resistance thereof will be approximately in proportion to the difference in potential between the current storage unit 42, and 41, or the unit 41, and 130

the unit 40. For example, the terminal potential of the unit 40, may be 8.8 volts, while the terminal potential of the unit 41, may be 6.6 volts, and the terminal potential of the 5 current storage unit 42, may be only 6.1 volts. Similarly in the case of the plate filter rectifier the transformer winding 5, will have a higher potential than the output potential of said filter. It will be noticed that this arrangement is suitable for 10 connection to any standard known type of radio set using one to eight or more vacuum tubes without requiring any changes in the usual operation, construction or arrangement of said radio set.

While the current storage units may be constructed in manner well known in the art, a preferred arrangement is indicated in Figure 2. A glass or rubber container 54, 20 is provided with a cover 70, which holds electrodes 56, 55, so that they are partly covered by the electrolyte or jellied electrolyte 57, contained in the container 54. The materials of 56, 55 and of 57, may be selected as 25 hereinbefore set forth to comprise either an electrolytic condenser or a secondary battery and one or more cells of the kind indicated by Figure 2, may comprise a current storage unit such as indicated by the numeral 30 40 in Figure 1. For example, if lead-acid-lead cells are used the storage unit 40, may have four such cells while the unit 41, has three cells and the unit 42, has three such cells. Or the unit 40 may comprise one or 35 two cells of the well known aluminum-alkaline-lead or tantalum-acid-lead type, while the unit 41, and the unit 42, comprise storage cells of the battery type, as set forth. In any case the unit 40, will be at a higher 40 potential than the unit 41, and the unit 41, will be at a higher potential than the unit 42. In this manner the units 41, and 42, are floated on the rectifier output but the choke coils arranged as set forth eliminate alternating 45 current ripples which would otherwise be objectionable in the radio set to which the radio power unit is to be connected. Even slight alternating current ripples are objectionable because they reach the sensitive grid 50 of a vacuum tube in a set to which the radio power unit is connected, and that is why at least two, and preferably three cascaded units, such as 40, 41, and 42, are used.

As indicated by Figure 2, the cell top 70,

is provided with a gas vent tube 58, and the 55 interior surface of this tube is preferably coated with platinum black or other chemical material, which can aid in partially absorbing or converting small amounts of gas 60 which occur during operation.

I claim:—

1. A radio power supply unit comprising a transformer, means to connect said transformer to a source of alternating current, a plate current supply fed by said transformer, a series cascaded filter connected to said plate current supply and including adjustable series resistances to adjust the output potential thereof and to prevent the sudden discharge of current therefrom, a filament 70 current supply fed by said source of alternating current, and a metallic container for enclosing said plate and filament current supplies and grounded to one of said supplies.

2. In a radio power supply unit, the combination of a transformer, filament and plate current supplies energized from said transformer, and means for suppressing magnetic lines of force extending from said transformer and associated apparatus, comprising a metallic container for enclosing said transformer and associated apparatus, said container being connected to one of the terminals of the filament current supply.

3. In a radio power supply unit, the combination of a transformer, a rectifier connected thereto, a filter circuit operatively connected to said rectifier, said filter circuit having a plurality of output terminals, and means for reducing the potential at the terminals of said filter circuit and limiting the rate of discharge of current therefrom, comprising resistances connected between the filter circuit and one or more of the output terminals.

4. In a radio power supply unit, the combination of a transformer, a plate current supply fed thereby, a filament current supply, and output terminals for each of said supplies, one of the terminals of the filament current supply being grounded, said plate current supply being isolated from said filament current supply except when the power supply unit is connected to a load.

In witness whereof, I have hereunto set my signature this 19th day of March, 1925.

PHILIP E. EDELMAN.
